OBSERVATION STAND FOR A TENNIS JUDGE

William W. White, Los Gatos, and Russell Davis, Palo Alto, Calif., assignors to Patterson-Williams Manufacturing Co.

Filed Dec. 9, 1974, Ser. No. 530,771

Term of patent 14 years

Int. Cl. D6—99

U.S. Cl. D6—4

FIG. 1

FIG _ 2

FIG _ 5

FIG _ 3

FIG. 1 is a front, top and left side perspective view of an observation stand for a tennis judge showing our new design;

FIG. 2 is a plan elevational view;

FIG. 3 is a front elevational view;

FIG. 4 is a left side elevational view, the right side being a mirror image thereof; and

FIG. 5 is a bottom plan view.

FIGS. 2 through 5 are reduced in scale from FIG. 1.

We claim:

The ornamental design for an observation stand for a tennis judge, as shown and described.
